DB-347. OR D12,050 EX

19. 12. 1951.

Dec. 7, 1951

UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A KEY-BOW.

SPECIFICATION forming part of Design No. 12,050, dated December 7, 1880.

Application filed September 27, 1880. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for Key-Bows, of which the following is a specification, reference being had to the accompanying wood engraving, forming part thereof.

10 The leading feature of my design consists in a semicircular bow resting upon a horizontal paneled bar and inclosing two conventional fern-leaves springing from the center of the base and inclining to the right and left hand, as hereinafter more fully described.

15 On the shank of the key is placed a horizontal bar, A, having a sunken and ribbed panel. Above this bar and resting upon its flat side

is the semicircular bow B, which incloses two conventional fern-leaves, C C, springing from the center and inclining to the right and left hand, and filling the corners. Each of these leaves is intersected by a sunken line, ribbed as shown.

I claim—

25 The design for a key-bow herein shown and described, the same consisting of the horizontal bar A, the semicircular bow B, inclosing the two conventional fern-leaves C C, inclining to the right and left hand and filling the corners, said leaves being intersected by sunken ribbed lines.

GEORGE SLATER BARKENTIN.
